UNITED STATES PATENT OFFICE.

EUGENE DE KLEIST, OF NORTH TONAWANDA, NEW YORK.

PNEUMATIC MUSICAL INSTRUMENT.

No. 877,203.

Specification of Letters Patent.

Patented Jan. 21, 1908.

Application filed January 13, 1906. Serial No. 295,914.

To all whom it may concern:

Be it known that I, EUGENE DE KLEIST, a citizen of the United States, residing at North Tonawanda, in the county of Niagara and State of New York, have invented a new and useful Improvement in Pneumatic Musical Instruments, of which the following is a specification.

This invention relates to automatic musical instruments which are driven by an electric motor and in which the motor-circuit is closed by a coin, which is detained in a chute or hopper for a sufficient time to cause the instrument to play one or more tunes, at the end of which period the coin is automatically released, thus breaking the motor-circuit and stopping the instrument. A coin-releasing mechanism of this character is shown and described in Letters Patent of the United States No. 713,653 granted to me November 18, 1902.

The present improvement is designed more especially for use in connection with pneumatic musical instruments employing a perforated music sheet and having means for automatically rewinding the same, and its object is to provide the instrument with simple means for automatically controlling the release of the coin deposited for playing the last tune on the music sheet so as to keep the motor and main suction bellows in operation after the wind chest has been cut off and until the music sheet has been rewound.

In the accompanying drawings consisting of 3 sheets: Figure 1 is a fragmentary front elevation of a pneumatic piano embodying the invention. Fig. 2 is an enlarged side elevation of the auxiliary wind chest, showing the position of the parts when the cut off valve is closed. Fig. 3 is a vertical longitudinal section of said auxiliary chest, with the parts in the same position. Fig. 4 is a transverse vertical section in line 4—4, Fig. 3 showing the unlocking pneumatic collapsed. Fig. 5 is an enlarged front view of the tracker board and coöperating devices, showing the means for actuating the valve of the auxiliary tracker mechanism. Fig. 6 is a transverse section in line 6—6, Fig. 5. Fig. 7 is a transverse section of the auxiliary wind-chest in line 7—7, Fig. 3. Fig. 8 is a face view of the coin hopper and coöperating releasing-pneumatics. Fig. 9 is a horizontal section in line 9—9, Fig. 8. Similar letters of reference indicate cor-

responding parts throughout the several views.

The piano action and the usual motor pneumatics which operate its hammers are not shown in the drawings and may be of any ordinary construction. The main wind chest, shown at A, and its valve mechanism may be of any suitable or well-known construction.

B indicates the usual tracker-board, C the perforated music sheet wound on the customary rollers c, c', D the air motor and E the driving gear of ordinary construction by which motion is transmitted from the motor to said rollers and which contains the usual reversing means controlled by the tracker board and music-sheet, for automatically rewinding the latter after the last tune or the same has been played.

F is the main suction bellows and G a cut-off device of any suitable or well known construction controlled by the tracker board and the music sheet and serving to cut-off communication between said bellows and the main wind-chest while the music sheet is being rewound.

H indicates the coin-chute, and I the coin-hopper or intercepting device which controls the circuit I' in which the electric motor I² of the instrument is included. This coin-intercepting device is preferably constructed substantially like that described and shown in the Letters Patent hereinbefore referred to and consists of a hopper or receptacle arranged at the foot of the chute H and having two opposite metallic walls i forming the terminals of the motor-circuit and adapted to be connected by a deposited coin which bears edgewise against said walls, the latter being arranged so closely together that the coin cannot drop through the throat between them. The other two walls of this hopper are made of insulating material, and one of them consists of a hinged door i' through which the intercepted coin is discharged laterally by an ejecting finger i² carried by said door and extending through a slot in the hopper wall opposite the door, so that when the latter is opened the ejector moves across the throat and expels the coin from the hopper. The hopper-door is controlled by either of two bellows or pneumatics J, J', the movable boards of which are connected with the door by rods j. For distinction, these bellows may be termed the main-coin discharge and

an auxiliary coin-discharge pneumatic, respectively. The main discharge pneumatic J, is controlled by the music-sheet and one of the units or valve chambers of the main wind-chest A in such manner that said pneumatic is collapsed and caused to open the hopper-door at the end of every tune, except the last, so as to cause the instrument to play a tune for each deposit of a proper coin.

- 10 The auxiliary coin-discharge pneumatic J' is adapted to come into action after the main wind-chest has been cut-off from the main suction bellows F and the music-sheet has been rewound. To furnish the necessary power for thus operating the last named pneumatic independently of the main wind-chest, I provide an auxiliary wind-chest K which is arranged in any suitable or accessible part of the instrument, the preferred location being at the left hand side of the tracker mechanism, as shown in Fig. 1. The chest K is provided with a main exhaust channel or chamber L Figs. 3, 4 and 7, which is constantly and directly connected with the main suction-bellows F by a tube l. This channel, which is preferably in the lower portion of the chest, leads to the bottom of an exhaust chamber M and is controlled by a cut-off valve m preferably of the rocking type arranged in said chamber. This valve is normally closed by a spring m'. It is opened by the movable board of a bellows or pneumatic N which is connected by a rod n with a vertically swinging arm N' which in turn acts upon the tail of the valve through a sticker n' passing through the top of the exhaust chamber. The arm N' is preferably provided on its underside with a strip n² of leather or similar material adapted to cover the hole through which said sticker passes, so as to exclude the outer atmosphere at this point when the arm is lowered, as shown by dotted lines in Fig. 3. This arm is pivoted in a chamber o arranged above the exhaust chamber M and passes through an opening o' in the end thereof which admits the outer air to the chamber o. The pneumatic N is connected by a tube p with one of the units or valve chamber of the main wind-chest A, in the same manner as the motor-pneumatics of the piano hammers and the music sheet has a corresponding perforation arranged to register with the companion duct of the tracker-board, when the instrument has about finished playing the last piece on the music sheet, so as to collapse said pneumatic and cause it to open the cut-off valve m. To avoid the formation of a long slot in the music sheet for this purpose, a suitable locking device is preferably employed
- 20 to keep the valve m open during the desired interval after having been opened by the pneumatic. The device shown in the drawings consists of a lever or catch q pivoted to the auxiliary wind chest and having a shoulder q' adapted to engage over the projecting

end of the arm N' when the latter is depressed, as shown by dotted lines in Fig. 2. A spring q² which connects the lower arm of the locking lever with the chest K serves to hold the lever in engagement with said arm.

R is an unlocking pneumatic arranged to disengage the locking lever q from the arm N' after the coin for the last piece on the music sheet has been released from the coin hopper I. This pneumatic is constantly connected with the main suction bellows F by communicating with the exhaust channel L, whereby when the main suction bellows is operated the unlocking pneumatic is collapsed, thus withdrawing its movable arm r' from the lower arm of the locking lever, while when said pneumatic is allowed to expand by the stopping of the instrument, said arm bears against the lever and unlocks the same, as shown by full lines in Fig. 2.

S is a valve chamber arranged in the auxiliary wind chest above the exhaust chamber M and connected with the latter by a port s and with the air chamber o by a port s'. The auxiliary or final coin discharge pneumatic J' is connected with this valve chamber by a tube s². The ports s, s' are controlled by valves s³, s⁴ arranged to close alternately, so that when the valve chamber is placed in communication with the exhaust chamber M it is shut off from the atmosphere, and vice versa. These valves are controlled by a diaphragm or pneumatic s⁵ arranged in the exhaust chamber and covering a pouch chamber s⁶.

Fig. 6, indicates a vent-channel or auxiliary tracker-duct arranged adjacent to the take-up roller c', and t' is a tube connecting said duct with the chamber s⁸ under the diaphragm s⁵s. This duct is normally closed by a valve t² having a suitable closing-spring t³. u is an arm or pawl pivoted to the base of the main tracker-board B in front of the tracker-valve l' and provided on its inner side with a finger u¹ adapted to bear upon the tail of said valve for opening it. The arm u is pressed toward the take-up roller by a spring u², and the roller is provided opposite the arm with an annular groove u³ which is entered by the free end of the arm when the groove is uncovered by the rewinding of the music sheet, thus permitting the arm to swing inwardly and opening the tracker-valve, while when the sheet is wound upon the take-up roller it moves the arm out of the groove, thereby withdrawing the finger u¹ from the tracker-valve and permitting the latter to close.

The operation of the parts is as follows:— Upon depositing a proper coin in the chute II, the motor circuit is closed and the motor is caused to operate the main suction bellows F in well known manner, exhausting the air from the exhaust channel L and the unlocking pneumatic R and collapsing the

latter, as shown in Fig. 4. From the time that the instrument begins to play until the last tune on the music sheet has been finished or nearly finished, the valve opening pneumatic N remains expanded, allowing the cut-off valve m to remain closed and the exhaust and vent valves s³ s⁴ to assume the position shown in Fig. 4. As the traveling music sheet covers the groove u³ of the take-up 10 roller under these conditions, the arm u is held in its inoperative position and the tracker valve t² is permitted to close. At the end of each tune, except the last, the deposited coin is discharged by the collapse of 15 the main discharge pneumatic J due to the action of the music sheet and the corresponding valve mechanism of the main wind chest as hereinbefore described. At about the end of the last tune, the pneumatic N is col- 20 lapsed by the action of the music sheet and locked by the lever q thereby opening the cut-off valve m and exhausting the air from the chamber M, preparatory to actuating the final or auxiliary coin-discharge pneumatic 25 J'. The last tune having been finished, the music sheet is automatically rewound in the customary manner and as soon as it uncovers the groove u³ in the take up roller, the arm u swings forwardly into the same, open- 30 ing the tracker-valve t², admitting the atmosphere under the diaphragm s⁵ and reversing the latter. By this action, the exhaust valve s⁴ is opened and the vent-valve s³ closed, thus placing the auxiliary coin dis- 35 charge pneumatic J' in communication with the exhaust chamber M, collapsing said pneumatic, discharging the coin from the hopper H and stopping the instrument. The air being now no longer exhausted from the 40 unlocking pneumatic R, the same expands and disengages the locking lever q from the arm N' allowing the pneumatic N to expand and the cut-off valve to close and restoring the parts to their former condition, ready to 45 repeat the above described cycle of operations.

I claim as my invention:

1. In a pneumatic musical instrument, the combination of a main exhaust bellows, a 50 motor therefor, coin - controlled means for starting and stopping the motor, including a coin-releasing pneumatic, a main wind-chest and coöperating tracker-mechanism, and an auxiliary wind-chest and coöperating tracker- 55 mechanism controlling said coin - releasing pneumatic and controlled by the main tracker-mechanism, substantially as set forth.

2. In a pneumatic musical instrument, the combination of a main exhaust bellows, a 60 motor therefor, coin - controlled means for starting and stopping the motor, including a main and an auxiliary coin-releasing pneu- 65 matic, a main wind - chest and coöperating tracker - mechanism controlling said main coin-releasing pneumatic, and an auxiliary

wind-chest and coöperating tracker-mechanism controlled by the main tracker mechanism and controlling said auxiliary coin-releasing pneumatic, substantially as set forth. 70

3. In a pneumatic musical instrument, the combination of a main exhaust bellows, a 75 motor therefor, coin - controlled means for starting and stopping the motor, including a coin-releasing pneumatic, a main wind-chest, tracker-mechanism coöperating with 80 said chest and including a take-up roller for the music sheet, said roller being provided with a groove adapted to be covered by the music-sheet, an auxiliary wind-chest connected with said main bellows and said coin- 85 releasing pneumatic, valve mechanism ar- ranged in said auxiliary chest and controlling communication between said main bellows and the coin-releasing pneumatic, an auxil- 90 iary tracker device having a duct leading to the last-named wind - chest, a valve control- 95 ling said duct, and an opening device for said valve arranged to enter said groove and normally held out of the same by the overlying music sheet, substantially as set forth. 100

4. In a pneumatic musical instrument, the combination of a main exhaust bellows, a 105 motor therefor, coin - controlled means for starting and stopping the motor, including a coin-releasing pneumatic, a main wind-chest, tracker - mechanism coöperating with said chest and including a take-up roller for the music sheet, said roller being provided with an annular groove adapted to be covered by the music sheet, an auxiliary wind-chest con- 110 nected with said main bellows and said coin- 115 releasing pneumatic valve mechanism ar- ranged in said auxiliary chest and controlling communication between the said main bel- 120 llows and the coin-releasing pneumatic, an auxiliary tracker device having a duct lead- 125 ing to the last-named wind-chest, a valve controlling said duct, a pivoted arm acting upon said valve and arranged opposite said groove, and a spring tending to move said arm into said groove, substantially as set forth. 130

5. In a pneumatic musical instrument, the combination of a main exhaust bellows, a 135 motor therefor, coin - controlled means for starting and stopping the motor, including a coin-releasing pneumatic, a main wind-chest, tracker - mechanism coöperating with said chest and including a take-up roller for the music sheet, said roller being provided with an annular groove adapted to be covered by the music-sheet, an auxiliary wind-chest connected with said main bellows and said coin-releasing pneumatic valve mechanism ar- 140 ranged in said auxiliary chest and control- 145 ling communication between the said main bellows and the coin-releasing pneumatic, an auxiliary tracker device having a duct leading to the last-named wind chest, a valve controlling said duct, and arranged adjacent 150

to the take-up roller, and a pivoted arm arranged opposite said groove and provided with a finger which acts upon said valve and opens it when the arm enters the groove, substantially as set forth.

6. In a pneumatic musical instrument, the combination of a main exhaust bellows, a motor therefor, coin-controlled means for starting and stopping the motor, including a 10 coin-releasing pneumatic, a main wind chest and coöperating tracker-mechanism, an auxiliary wind chest having an exhaust channel connected with said main bellows, an exhaust chamber connected with said channel a cut-off valve controlling communication between said chamber and channel a pneumatic for opening said valve controlled by said main wind-chest and tracker-mechanism, a valve chamber connected with said exhaust chamber and said coin-releasing pneumatic and having an exhaust valve and a vent-valve, a diaphragm or pneumatic arranged in said exhaust chamber and controlling the last named valves, an auxiliary tracker device having a 20 duct leading to said diaphragm, and a valve controlling said tracker-duct and controlled by said main tracker mechanism, substantially as set forth.

7. In a pneumatic musical instrument, the combination of a main exhaust bellows, a motor therefor, coin controlled means for starting and stopping the motor, including a coin - releasing pneumatic, a main wind chest and coöperating tracker mechanism, 30 an auxiliary wind chest having an exhaust channel connected with said main bellows, an exhaust chamber connected with said channel a cut-off valve controlling communication between said channel and chamber, a 35 pneumatic for opening said valve controlled by said main wind chest and tracker mechanism, a locking device for holding said valve in its open position, a valve chamber connected with said exhaust chamber and 40 said coin-releasing pneumatic and having an exhaust valve and a vent - valve, and an auxiliary tracker device controlling the last named valves and controlled by said main tracker-mechanism, and an unlocking pneumatic connected with said main bellows and 45 acting on said locking device, substantially as set forth.

8. In a pneumatic musical instrument, the combination of a main exhaust bellows, a motor therefor, coin controlled means for starting and stopping the motor, including a coin - releasing pneumatic, a main wind chest and coöperating tracker mechanism, an auxiliary wind chest having an exhaust channel connected with said main bellows, an exhaust chamber connected with said channel a cut-off valve controlling communication between said channel and chamber a pneumatic for opening said valve controlled by 55 said main wind chest and tracker mechanism,

ism, a pivoted arm arranged outside of said exhaust chamber and actuated by the last-named pneumatic, a rod interposed between said arm and said cut off valve, a locking lever coöperating with said arm, an unlocking pneumatic connected with said main bellows and acting on said locking lever, valve mechanism in said auxiliary wind chest controlling communication between said exhaust chamber and said coin-releasing pneumatic, and an auxiliary tracker mechanism controlling said valve mechanism and controlled by said main tracker mechanism, substantially as set forth.

9. In a pneumatic musical instrument, the combination of a main exhaust bellows, a motor therefor, coin controlled means for starting and stopping the motor, including a coin-releasing pneumatic, a main wind chest and coöperating tracker mechanism, an auxiliary wind chest having an exhaust channel connected with said main bellows, an exhaust chamber connected with said channel a cut-off valve controlling communication between said channel, and chamber, a pneumatic for opening said valve controlled by said main wind chest and tracker mechanism, a pivoted arm arranged outside of said exhaust chamber and actuated by the last-named pneumatic, a rod interposed between said arm and said cut-off valve, a locking lever coöperating with said arm, an unlocking pneumatic connected with said main bellows and acting on said locking lever, a valve chamber connected with said exhaust chamber and said coin releasing pneumatic and having an exhaust and a vent - valve, a diaphragm or pneumatic arranged in said exhaust chamber and controlling the last named valves, an auxiliary tracker device having a duct leading to said diaphragm and a valve controlling said tracker duct and controlled by said main tracker mechanism, substantially as set forth.

10. In a pneumatic musical instrument, having coin controlled means for stopping and starting the motor of its main suction bellows, including a coin - releasing pneumatic, an auxiliary wind chest having an exhaust chamber, an exhaust channel leading to said chamber, a cut off valve controlling communication between said chamber and said channel, a pneumatic for opening said valve adapted to be controlled by the main wind chest and tracker mechanism of the instrument, a valve chamber adapted to be connected with said coin - releasing pneumatic and having ports leading to said exhaust chamber and the outer atmosphere, valves controlling said ports, and a diaphragm arranged in said exhaust chamber and controlling the last named valves, the chamber below said diaphragm having a passage for admitting the atmosphere, substantially as set forth.

11. In a pneumatic musical instrument, having coin controlled means for stopping and starting the motor of its main suction bellows, including a coin-releasing pneumatic, an auxiliary wind chest having an exhaust chamber, an exhaust channel leading to said chamber, a cut-off valve controlling communication between said chamber and said channel, a pneumatic for opening said valve adapted to be controlled by the main wind chest and tracker mechanism of the instrument, an auxiliary wind chest having an exhaust chamber, an exhaust channel leading to said chamber, a cut-off valve controlling communication between said chamber and said channel, a pneumatic for opening said valve adapted to be controlled by the main wind chest and tracker mechanism of the instrument, a lever for locking said valve in its open position, an unlocking pneumatic adapted to be connected with the main suction bellows of the instrument and acting on said lever, a valve chamber adapted to be connected with said coin-releasing pneumatic and having ports leading to said exhaust chamber and the outer atmosphere, valves controlling said ports, and a diaphragm arranged in said exhaust chamber and controlling the last named valves, the chamber below said diaphragm having a passage for admitting the atmosphere, substantially as set forth.

12. In a pneumatic musical instrument having a coin controlled means for stopping and starting the motor of its main suction bellows, including a coin-releasing pneumatic, an auxiliary wind chest having an exhaust chamber, an exhaust channel leading to said chamber, a cut-off valve controlling communication between said chamber and said channel, a pneumatic for opening said valve adapted to be controlled by the main wind chest and tracker mechanism of the instrument, a sticker acting upon said valve and passing through an opening in the top of the exhaust chamber, an arm bearing upon the projecting end of said sticker and operatively connected with the last-named pneumatic, said arm being arranged to close the opening through which the sticker passes, when depressed, a locking lever coöperating with said arm, an unlocking pneumatic acting on said lever and adapted to be connected with the main suction bellows of the instrument, a valve chamber adapted to be connected with said coin-releasing pneumatic and having ports leading to said exhaust chamber and the atmosphere, valves controlling said ports and a diaphragm arranged in said exhaust chamber and controlling the last named valves, substantially as set forth.
